UNITED STATES PATENT OFFICE.

ROBERT B. QUINN, OF COLUMBUS, OHIO, ASSIGNOR OF ONE-HALF TO TONKIE A. QUINN,
OF CHARLESTON, WEST VIRGINIA.

WRENCH.

1,270,746.

Specification of Letters Patent. Patented June 25, 1918.

Application filed April 10, 1918. Serial No. 227,766.

To all whom it may concern:

Be it known that I, ROBERT B. QUINN, a citizen of the United States, residing at Columbus, in the county of Franklin and State 5 of Ohio, have invented certain new and useful Improvements in Wrenches, of which the following is a specification, reference being had to the accompanying drawings.

This invention relates to certain improvements in wrenches and has relation more particularly to a device of this general character including a sliding jaw held in its various adjustments through the medium of a toothed rack catch and it is an object of the 10 invention to provide a device of this general character having novel and improved means whereby the sliding jaw is effectively maintained in its different adjustments under the influence of the strain or pull imposed thereon during a working operation.

It is also an object of the invention to provide a novel and improved wrench of this general character wherein a materially greater separating movement may be imparted to the jaws of the wrench in comparison with the other types of similar wrenches now generally in use.

It is also an object of the invention to provide a novel and improved wrench of this 25 general character wherein the rack catch is normally urged toward the rack through the medium of an expandible member together with parts carried by the rack for contact with the sliding jaw so that the teeth of the 30 sliding catch are relieved of strain during a working operation.

The invention consists in the details of construction and in the combination and arrangement of the several parts of my improved wrench whereby certain important 40 advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

Figure 1 is a view in side elevation with an end portion broken away of a wrench constructed in accordance with an embodiment of my invention, the jaws being shown separated;

55

Fig. 2 is a fragmentary view partly in longitudinal section and partly in elevation showing the coacting structure of the shank and movable jaws; and

Fig. 3 is a sectional view taken substantially on the line 3—3 of Fig. 1.

As disclosed in the accompanying drawings S denotes a shank of my improved wrench provided at its outer end with the rigid jaw J. The opposite end portion is 65 adapted to have engaged therewith in any desired manner a grip or hand grasp G. This grip or hand grasp, however, forms no part of my present invention and for this reason it is believed to be unnecessary to 70 give a detailed description and illustration thereof.

M denotes a movable jaw slidably engaged with the shank S through the medium of the jaw J and the hand grasp or grip G and 75 the opening 1 of the jaw M through which the shank S is directed is of a length slightly in excess of the width of the shank S so that the jaw M is capable of slight movement transversely of the shank S independently 80 thereof.

The outer face of the extended portion of the jaw M is recessed as indicated at 2 and the side walls of said recess at a point in close proximity to the shank S are provided 85 with the spaced ears 3. Engaged with the ears 3 is a pivot member 4 preferably removable and with which the catch C is engaged for rocking movement. The inner marginal portions of the ears 3 or the marginal portions thereof opposed to the shank S are rounded as at 5 with the curvature concentric to the pivoted pin 4.

The face or edge of the shank S opposed to the catch C is provided with a rack R 95 extending from a point in close proximity to the jaw J to the hand grasp or grip G and the teeth in said rack are correspondingly beveled in a direction so that the movable jaw M may have free and unobstructed 100

movement toward the jaw J and whereby the catch C will effectively interlock with the teeth of the rack R when pull or strain is imposed upon the shank S during a working operation.

The working end of the catch C is flat and snugly overlies the rack R and said working face is provided with the outstanding teeth 6 disposed transversely thereof and 10 which interlock with the teeth of the rack R.

The working end portion of the catch C is provided with the oppositely directed lugs 8 which overlie the ears 3 and arranged for contact therewith. The contacting surfaces of the lugs 8 are rounded in accordance with the curvature of the inner marginal portions of the ears 3 so that when pull or strain is imposed upon the shank S during a working operation, the lugs 8 will 15 be forced between the ears 3 and the adjacent edge or face of the shank S so that the strain or pull effected during the operation will assure the desired coaction of the catch C and the rack R for holding the jaw M against movement after being set for proper 20 engagement with the work.

It is also preferred that the opening 10 in the catch C through which the pivot member or bolt 4 is passed be of a diameter 30 slightly in excess of the diameter of the pin so that the catch C will have slight free or independent movement. This free or independent movement is of especial advantage as it assures the proper positioning of the lugs 8 between the ears 3 and the shank S for relieving the pivot pin 4 from strain. The catch C is provided with an outwardly directed tail portion 11 and interposed between said tail portion 11 and the base of 40 the recess 2 is an expansible member 12 herein disclosed as a conventional coil spring. The tension of the member 12 is such as to constantly urge the working face of the catch C toward the rack R. It is 45 to be emphasized at this time, however, that the expansible member 12 is not for the purpose of effecting the desired locking action between the catch C and the rack R as this is effected entirely through the medium 50 of the pull or strain imposed upon the shank. It is to be understood, however, that the tension of the member 12 is sufficient to effect an initial interlock so that the jaw M will be maintained in its proper adjustment 55 relative to the jaw J and in accordance with the size or the character of the work with which the wrench is to be employed.

It is also to be particularly noted that the ears 3 are relatively small and this is of 60 especial import as it permits the greatest possible range of movement of the jaw M relative to the jaw J. In practice it has been found that with a twelve inch wrench

the jaw M as herein disclosed is capable of movement of four and one-half inches at 65 any point therebetween. By this provision it will be at once self-evident that the usages of my improved wrench are manifold as it can be readily employed with comparatively light or heavy work.

From the foregoing description, it is thought to be obvious that a wrench constructed in accordance with my invention is particularly well adapted for use by reason of the convenience and facility with which 70 it may be assembled and operated and it will also be obvious that my invention is susceptible of some change and modification without departing from the principles and spirit thereof and for this reason I do not 75 wish to be understood as limiting myself to the precise arrangement and formation of the several parts herein shown in carrying out my invention in practice except as hereinafter claimed.

I claim:

1. A wrench, in combination with a shank provided with a rigid jaw, a movable jaw 90 slidably engaged with the shank and capable of slight rocking movement independently of the shank, spaced ears carried by the movable jaw outwardly of the shank, a catch pivotally engaged between the ears, the working end of the catch and the adjacent face of the shank being provided with 95 interlocking teeth, the inner marginal portions of the ears of the movable jaw being rounded, the working end of the catch being provided with oppositely directed lugs arranged for contact with the rounded portions of the ears, the contacting faces of the lugs being curved correspondingly to the rounded faces of the ears whereby pressure is imposed directly upon the working end portion of the catch for maintaining the 100 same locked to the shank when pull is imposed upon the wrench and the jaws engaged with the work, and means for constantly urging the working end of the catch toward the shank.

2. A wrench, in combination with a shank provided with a rigid jaw, a movable jaw 115 slidably engaged with the shank and capable of slight rocking movement independently of the shank, spaced ears carried by the movable jaw outwardly of the shank, a catch pivotally engaged between the ears, the working end of the catch and the adjacent face of the shank being provided with interlocking teeth, the inner marginal portions of the ears of the movable jaw being rounded, the working end of the catch being provided with oppositely directed lugs arranged for contact with the rounded portions of the ears, the contacting faces of 120 the lugs being curved correspondingly to the

the rounded faces of the ears whereby pressure is imposed directly upon the working end portion of the catch for maintaining the same locked to the shank when pull is imposed upon the wrench and the jaws engaged with the work, and means for constantly urging the working end of the catch toward the shank, said catch being pivoted with the movable jaw by a pin carried by 10 the jaw and disposed through an opening in

the catch, the opening in the catch being of a diameter slightly in excess of the diameter of the pin.

In testimony whereof I hereunto affix my signature in the presence of two witnesses. 15

ROBERT B. QUINN.
